(57) **CLAIM**

The ornamental design for a catch basin assembly for flowable product applicator, as shown and described.

DESCRIPTION

The catch basin assembly for flowable product applicator is used to hold a supply of pellets or granules and deliver metered amounts of the flowable product to an appropriate applicator.

FIG. 1 is a front, right, top isometric view of a catch basin assembly for flowable product applicator showing my new design;

FIG. 2 is a rear, left, top isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.
